UNITED STATES PATENT OFFICE.

MANUEL MONTOYA, OF NEW YORK, N. Y.

MUSICAL INSTRUMENT.

SPECIFICATION forming part of Letters Patent No. 653,521, dated July 10, 1900.

Application filed June 6, 1899. Serial No. 719,593. (No model.)

To all whom it may concern:

Be it known that I, MANUEL MONTOYA, a citizen of the United States of Colombia, and a resident of the city of New York, borough 5 of Manhattan, in the county and State of New York, have invented a new and Improved Musical Instrument, of which the following is a full, clear, and exact description.

The invention relates to stringed musical 10 instruments, particularly those of the guitar and mandolin type, and has for its objects, first, to provide an improved construction of the body of the instrument, and, second, to provide an improved tailpiece for securing 15 the strings.

To this end my invention consists in the novel construction and arrangement of parts hereinafter described and claimed.

Reference is to be had to the accompanying 20 drawings, forming a part of this specification, in which similar characters of reference indicate corresponding parts in all the figures.

Figure 1 is a plan view of the musical instrument constructed according to my invention. Fig. 2 is a longitudinal sectional elevation thereof. Fig. 3 is a sectional plan of the body. Fig. 4 is a detail sectional plan of a portion of the body. Fig. 5 is a plan of the tailpiece, and Fig. 6 is an end view thereof.

The instrument comprises the body A and the neck B, which carries the tuning-pegs C. The tuning-pegs and neck may be constructed in any well-known or approved manner. The body A has an approximately-horizontal top 25 A', strengthened by transverse ribs A² and provided with the usual sound-hole A³. On said top rests the bridge D, which may be of the usual construction. The bottom A⁴ of the body is curved both longitudinally and transversely, and between the bottom and top is interposed a vertical wall which I construct 30 of two layers, the outer one of which, A⁵, consists of celluloid, while the inner one, A⁶, is made of wood, the two layers to be glued together, so that they will vibrate in unison 35 and not independently. Also with this construction the vertical wall will be strong and light.

To strengthen the body, I provide it with 40 a neckpiece A⁷, having a suitable dovetailed groove A⁸ for connection with the neck B, and at the opposite end with a headpiece A⁹.

These two pieces extend from the top A' to the bottom A⁴ to engage both of them, and they are also in engagement with the vertical 55 walls A⁵ A⁶. The headpiece A⁹ and the neckpiece A⁷ are connected by braces A¹⁰, extending at equal distances from the longitudinal axis of the instrument and parallel therewith, and said braces at their central portions are 60 reduced in thickness, while at their ends they are enlarged to substantially the height of the headpiece A⁹ and the neckpiece A⁷, respectively. Thus the braces A¹⁰ do not engage the top A and bottom at all or only just at 65 the points where they connect with the headpiece A⁹ and the neckpiece A⁷. The vibrations of the top and bottom are therefore not interfered with in the least.

The strings E after passing over the bridge, 70 D are secured to the tailpiece F, which is made in the shape of a lyre and has at its front end a series of notches F', through which the strings are adapted to pass, also apertures F² with notches F³ corresponding to the notches F', so 75 that the strings may be passed through said notches and securely held by the projection F⁴, located between the notches F³. Upon the said tailpiece F, I secure a series of tuning-tongues G, corresponding in number to the 80 strings of the instrument. Thus in a guitar I provide six tuning-tongues G. These may be of the same kind as those employed in music-boxes; but any other suitable vibrating device may be employed. The tongues G 85 may be separated by strings H, which also enhance the ornamental appearance of the instrument. The tongues are so tuned as to give when sounded the notes according to which the strings of the instrument ought to 90 be tuned. I may also secure upon the tailpiece an additional vibrator or tuning-tongue G' to indicate the fundamental "A."

To prevent the tongues from being picked or struck by accident, I may extend over them 95 a guard or shield, such as indicated by the letter G². It will be understood that the vibrators G G' are to be sounded with the fingers or with a pick, according to the nature of the instrument on which they are applied. 100

It will be seen that by my invention I provide a very strong construction of the body without interfering with its resonating qualities, and at the same time I provide a ready

means for absolutely-correct tuning of the strings.

Having thus fully described my invention, I claim as new and desire to secure by Letters

5 Patent—

- 10 1. A musical instrument, provided with a hollow body comprising a top and bottom, and a peripheral wall connecting said top and bottom, said peripheral wall consisting of an outer layer of celluloid and an inner layer of wood glued together, substantially as shown and described.
- 15 2. A musical instrument, provided with a hollow body comprising a top and bottom, a peripheral wall connecting them, a headpiece and a neckpiece at opposite sides of said peripheral wall, and braces connecting said headpiece and neckpiece and arranged out of contact with the walls of the body, said braces being arranged at opposite sides of the

longitudinal axis of the instrument and reduced in thickness at their central portions, while at their ends they are extended upward and downward to approximately the height of the headpiece and neckpiece respectively, 25 substantially as shown and described.

3. A musical instrument, provided with a tailpiece having at its front end a series of notches for the passage of strings, and at the rear of said notches a series of apertures with 30 notches and projections between them, substantially as shown and described.

4. A musical instrument, comprising a body having a vibrating wall or resonator consisting of a layer of wood and a layer of celluloid 35 glued together to vibrate in unison.

MANUEL MONTOYA.
